UNITED STATES PATENT OFFICE.

JOSEPH A. WYLER, OF ALLENTOWN, PENNSYLVANIA, ASSIGNOR TO TROJAN POWDER COMPANY, OF NEW YORK, N. Y., A CORPORATION OF NEW YORK.

AMMONIUM-NITRATE EXPLOSIVE.

No Drawing.

Application filed March 23, 1926. Serial No. 96,874.

This invention relates to ammonium nitrate and to ammonium nitrate explosives, and the principal object of the invention is to provide by novel means ammonium nitrate the sensitiveness to detonation of which is relatively high.

I have discovered that hexamethylenetetramine when properly combined with ammonium nitrate has the effect of materially increasing the sensitiveness of this product toward detonation. For this purpose, I preferably use about 4% of the hexamethylenetetramine to 96% of ammonium nitrate, but I do not limit myself to these proportions, which may vary widely, depending upon the degree of sensitiveness desired and upon certain other controlling factors such as gas volume and brisance.

In practicing my invention, I have found it possible to combine the hexamethylenetetramine with the ammonium nitrate in various ways. I have found, for example, that a simple mixture of finely ground hexamethylenetetramine with dry crystals of ammonium nitrate will give the desired results, and as a specific example of this method of applying the sensitizing agent, I may take 96 parts of dry ammonium nitrate and mix therewith four parts of powdered or crystalline hexamethylenetetramine, the latter being thoroughly incorporated.

I may also cocrystallize the hexamethylenetetramine with the ammonium nitrate as follows: To 96 parts of ammonium nitrate add about 10 parts of water and 4 parts of hexamethylenetetramine. Heat this mixture in a steam-jacketed kettle with stirring until fine dry crystals are gotten. This is the sensitized product.

In another and preferred method for obtaining this cocrystallized mixture, I add to 576 parts of crystalline ammonium nitrate, 77 parts of a 40% solution of formaldehyde, warming the solution in a steam-jacketed kettle with stirring until about one-half of the ammonium nitrate has dissolved. I then add about 40 parts of 28% ammonium hydroxide solution. In this case the reaction between the formaldehyde, the ammonium nitrate and the ammonium hydroxide yields hexamethylenetetramine which on evapora-

tion crystallizes with the excess of ammonium nitrate to afford the cocrystallized mixture of ammonium nitrate and hexamethylenetetramine in the desired proportions.

Still other methods may be successfully employed in obtaining the required intimate mixture of ammonium nitrate and hexamethylenetetramine, and there is to be no limitation in this respect.

The following is an example of an explosive employing my sensitized ammonium nitrate:

	Per cent.
Nitrostarch	10.00 65
Ammonium nitrate	76.00
Hexamethylenetetramine	4.00
Sodium nitrate	9.55
Zinc oxide	.20
Hydrocarbon oil	.25 70

In making the explosive, the sensitized ammonium nitrate may be prepared in accordance with the procedure described above. This explosive has good sensitiveness to detonation from a detonator or "cap", but is relatively insensitive to ordinary blows and friction.

I claim:

1. An explosive comprising ammonium nitrate and hexamethylenetetramine.
2. An explosive comprising intimately admixed ammonium nitrate and hexamethylenetetramine.
3. An explosive comprising intercrystallized ammonium nitrate and hexamethylenetetramine.
4. As a new article of manufacture, ammonium nitrate sensitized with hexamethylenetetramine.
5. An explosive comprising ammonium nitrate and hexamethylenetetramine in relative proportions of approximately 1 part of hexamethylenetetramine to 24 parts of the nitrate.
6. An explosive comprising ammonium nitrate containing in cocrystallized form approximately 4% of its own weight of hexamethylenetetramine.
7. As a new article of manufacture, ammonium nitrate containing approximately 4% of its own weight of hexamethylenetetramine.

8. The method of sensitizing ammonium nitrate, which consists in mixing therewith hexamethylenetetramine.

9. The method of sensitizing ammonium nitrate, which consists in cocrystallizing therewith hexamethylenetetramine.

10. The method of sensitizing ammonium

nitrate, which consists in reacting ammonium nitrate with formaldehyde and ammonium hydroxide, and thereafter evaporating the solution to obtain a cocrystallized mass of ammonium nitrate and hexamethylenetetramine. 10

JOSEPH A. WYLER.
